UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK

TIME RECORDER

Application filed March 2, 1925. Serial No. 12,488.

The present invention relates to improvements in time recorders and is directed to general improvements in that class of recorders known as card recorders. The recorder which forms the subject matter of the present invention includes timing mechanism and spring motor driving mechanism assembled within a box frame; and recording mechanism comprising type wheels, card receiver and like parts, a clock dial unit and time train therefor, and a program wheel assembly, all mounted on a frame which is detachably secured to the main box frame.

Among the objects of the invention is to provide certain novel assembly features of a time recorder whereby the clock mechanism is split up with the time controlling mechanism to the rear and at the upper part of the unit and the power drive disposed at the bottom of the unit in close proximity to the operating lever. This assembly has the purpose in view of obtaining compactness, ease of adjustment and inspection, gain in operation efficiency, and smartness in appearance.

Another object is to assemble the recorder parts themselves within a compact volume on a frame which is supported in front of the clock mechanism and is readily removable as a complete unit for the purpose of assembling or adjusting the clock mechanism. Over the entire framework there is placed a removable cover which likewise may be connected to the main supporting box frame and preferably locked to the recorder supporting frame. With this arrangement of parts it is possible for a user to remove the cover of the recorder leaving all of the operating parts in position for inspection or minor repairs. If extensive repairs or replacements are required in the recorder mechanism it is possible, after the cover has been removed, to remove the framework of the recorder as a unit, thus removing all of the operating parts of the recorder which are carried thereby. If desired, substitutions of new complete recorder units can thus be readily made. With the recorder thus removed the clock parts, such as the pendulum, etc., are accessible for inspection or adjustment.

Another object is the provision of sub-

assembly units for the entire time recorder whereby these various sub-assembly units may be built up separately and then assembled into proper cooperation with each other. According to the present invention there is a recording unit comprising several separate assemblies, a clock unit, and a power unit all separately contained and removable.

Another object resides in the provision of suitable means by which a workman will introduce an increment of stored power in the spring motor upon every operation of the recorder lever until the spring motor is wound to a predetermined limit, at which limit the recorder lever will automatically become ineffective for further rewinding. When the spring power falls below another limit, rewinding by the recorder lever is again rendered possible.

Another object is the provision of a very accurate minute jumping mechanism which is capable of being easily and precisely adjusted and having the purpose of automatically driving the clock hands and recording mechanism at the elapse of one minute, or for automatically driving the same mechanisms at the end of any interval during which they might have been held from displacement, and for the equivalent length of the interval held up, without there being any interruption of operation of the clock.

Another object resides in the provision of a time jumping mechanism intermediate the spring motor drive and type wheels which will not cause an additional drag upon the spring motor or disturbance of the time controlling mechanism when the type wheels are held from rotation for an indefinite period of time.

Other objects involving novel constructions and combinations of parts will appear in the specification and in the claims thereof setting forth a preferred embodiment of my invention which will be fully understood from the detailed description and drawings, in which:

Fig. 1 is a view of the interior of the time recorder looking from the right; Fig. 1A is a detail of the friction connection of the rewind actuating pawl on line 1A—1A of Fig. 1.

travel, wedge-shaped stud 48 will come against the slanting face of pawl 49 and cam the pawl in a clockwise direction against the action of spring 50 until the top of the stud 5 passes the point of the pawl. At this instant the restraining force on spring 50 is eliminated and the spring will act to snap the slide to the right (Fig. 10), with the result that cam slot 38 raises the rear end of wishbone 10 member 30 and stud 32 thereon rocks member 25 and ratchet 26 counterclockwise to the position shown in Fig. 1.

In this position, ratchet wheel 18 will be actuated on every depression of operating lever 19, and gear 10 will be advanced in the direction of the arrow to wind the spring motor. As the spring motor is gradually rewound, gear 10 will rotate nut 44 counterclockwise and cause it to travel to the left 20 on the nearly non-rotating screw 45. Nut 44 will contact stud 42 and carry slide 34 to the left, as shown in Fig. 10, to the position where pawl 49 will be displaced to its maximum extent and then suddenly snap the slide 25 to the left, as seen in Fig. 11. This snap action causes pawl 26 to be suddenly disengaged from contact with ratchet wheel 18 and thus throw out the step-by-step automatic rewind of the operating lever 19.

The disengagement is obtained through the lowering of the rear end of wishbone member 30 when stud 39 is cammed downwardly thus causing member 25 to be positioned in its non-functioning position as described above. Set screws 51 are provided to adjust the timing relation between the snap action and ratchet positioning.

Power from the spring motor is distributed to the clock and recorder mechanisms by 40 means of gear 11 and through the intervention of pinion 52 and gear 53, both fixed to shaft 54 (Fig. 1). Gear 53 meshes directly with pinion 55 on shaft 56 which also carries beveled gear 57 fixed thereto. Beveled gear 45 57 meshes with another beveled gear 58 on the lower end of short shaft 59. This short shaft is mounted in a bracket 60 fastened to the left hand plate 7 and carries at its upper end a universal socket 61 for the reception 50 of the lower end of a universal shaft 62. This connection is readily severed as is also the connection between lever 22 and link 23 in order that the entire spring motor mechanism can be removed as a unit.

55 Shaft 62 is driven in a clockwise direction as seen from above, and its upper end rotates a short shaft 63 to which is pinned gear 64 supported by bracket 65. Gear 64 drives gear 66 (Fig. 4) secured to shaft 67, which is supported at its rear end by the base plate 68 of the clock frame. The front end of the shaft is supported by a sleeve 69 which in turn has a fixed bushing 70 as a bearing. 65 This bushing is tightly swaged in place in a

hole in the front plate 71 of the clock mechanism.

The two plates 68, 71 are held rigidly together by four screws 72 and spacing sleeves 73 forming the frame of the clock mechanism 79 (Figs. 3 and 4) which is separatively removable.

Loosely mounted on shaft 67 are two sleeves 69, 75, having respectively gears 76 and 77, comprising the two actuated gears of a differential. Pinned to shaft 67 is a spider 78 which has loosely mounted thereon a traveling bevel gear 79 through which motion is communicated from the shaft to beveled gears 76 and 77 with which it meshes. 80

There is rigidly fastened to sleeve 75 a gear wheel 80 meshing with a small gear 81 comprising a part of the train of gears leading from a Graham dead-beat escapement mechanism of the usual construction. The arbors 85 of this escapement mechanism are journaled in plates 68 and 82 which are held together by four bolts 83 and their spacing sleeves. 84 is the verge spindle to which is fastened one end of verge wire 85, while the other end is 90 fastened to pendulum 86.

Mounted on sleeve 75 is a cam bearing sleeve 87 which is held from relative movement with sleeve 75 and made to rotate therewith by reason of the frictional force exerted by spring washer 88 bearing against gear wheel 80. The flexibility of this connection is for the purpose of adjusting the exact moment of advance of the program wheel, type wheel and time indicating mechanism, as will 100 later be explained.

On sleeve 69 there is secured by a set screw 89 a jumping member 90 which carries stud 91 and gears 92 and 93 loosely journaled thereon. Gear 93 meshes with idler 105 gear 94 which in turn engages pinion 95 fixed to one end of shaft 96. This shaft is mounted in a bearing 97 on jumping member 90 and has a finger 98 pinned to the other end. This finger bears against the concentric surface 110 99 of cam 100 until the surface is removed from beneath it, at which event the pawl will rotate counterclockwise as seen in Fig. 8, and land upon the surface, Fig. 9, as will be later described. 101 is a mass of material integral with jumping member 90 and has the purpose of counterbalancing member 90 to insure uniform rotation.

There is fixed to stationary bushing 70 a large gear 102 which forms the track over 120 which pinion 92 travels.

The purpose of this train of mechanism is to produce follow-up actuations of the clock and recorder mechanisms at periodic intervals, and it operates in the following manner: Between the instantaneous advancements of the driven mechanisms, jumping member 90 is held stationary as is likewise beveled gear 76 of the differential. Spider 78 is being continuously driven by the spring 125 130

ing lugs 134 engage clips 135 secured to frame 2. A lock 136 is provided preferably in the cover for the purpose of insuring freedom from meddling and for affixing the responsibility of the maintenance and proper working condition of the time recorder on some particular individual.

While the form of mechanism herein shown and described is admirably adapted to fulfill the objects previously stated, it is to be understood that it is not intended to confine the invention to the one form of embodiment herein disclosed, for it is susceptible of embodiment in various forms all coming within the scope of the claims which follow.

What I claim is:

1. In a time recording apparatus having in combination, time type wheels adapted for step by step advance, which advance may be suppressed during the taking of a record from the type wheels, and means for driving the type wheels, connecting devices intermediate the said wheels and the driving means, said connecting devices having provisions for

20 transforming continuous motion from the driving means into an intermittent motion which is applicable to drive the type wheels in variable magnitudes dependent upon the lag of the type wheels with respect to the driving means following an interruption of motion of the type wheels so that the type wheels of the recorder reassume and preserve their proper relationship to the driving means irrespective of a suppression of an advance of the type wheels.

25 2. In a recording apparatus having type wheels and means for driving the same, the combination of connecting devices disposed intermediate the said wheels and the driving means, said connecting devices having provision for receiving motion from the driving means for advancing said wheels step-by-step and for causing said wheels to be advanced a variable magnitude after the step-by-step movement has been interrupted.

30 3. In a recording apparatus having type wheels and a time mechanism for positioning the same, the combination of an intermediate driving connection between the said mechanism and wheels, means in said connection for receiving continuous motion of advance from said mechanism and imparting stepped increments of advance to said wheels, said means having provisions for effecting an advance of said wheels in steps of variable magnitude which in duration and extent may exceed the normal step of advance of the wheels.

35 4. In a recording apparatus having type wheels and a time mechanism for positioning the same, the combination of an intermediate driving connection between the said mechanism and wheels, means in said connection for receiving continuous motion of advance from said mechanism and imparting

stepped increments of advance to said wheels, said means having provision for effecting an advance of said wheels after variable lapses of time exceeding in duration the interval of time represented between steps of advance 70 of the wheels during normal operation.

5. In a recording apparatus having printing elements and time mechanism for positioning the same, the combination of an intermediate connection between the said mechanism and printing elements, means in said connection driven at a constant rate by said time mechanism, jumping means which is driven intermittently the same distance by said timing mechanism, means for 80 allowing said jumping mechanism to be driven a variable distance to catch up with said first mentioned means after the intermittent drive of the jumping mechanism has been interrupted, and means to connect said 85 last mentioned means with the printing elements.

6. In a recording apparatus having printing elements and time mechanism for positioning the same, the combination of a motion-transforming connection interposed between the said mechanism and printing elements, means in said connection driven by said timing mechanism, and means controlled by said first mentioned means for advancing 90 in periodic intervals the printing elements and for advancing said elements the distance covered by the first mentioned means during a period greater than the normal period of 95 operation of the printing elements subsequently to an interruption of the periodic advance of the printing elements.

7. In a recording device, the combination of a follow-up mechanism comprising a source of power, a constantly rotating means 100 operated from said source of power, timing mechanism for controlling the rate of rotation of said means, jumping mechanism driven by said means and capable of differential advance, means on said first mentioned 105 means controlling the actuation of said jumping means, and recording mechanism driven concurrently with said jumping means.

8. In a recording device, the combination of a follow-up mechanism comprising drive 110 means, a driven member revolubly mounted on said drive means, a cam adjustable on said driven member, a second driven member, means carried by said second driven member and controlled by said cam for preventing 115 rotation of said second driven member during a definite amount of rotation of said cam.

9. In a recording apparatus, the combination comprising time indicating means, a 120 driving element, means for causing the indicating means to be driven in timed relationship by the driving element, and means controlled solely by said means for restoring 125 said time relationship between said indicating means.

in harmony with the escapement controlled parts.

20. A time controlled apparatus including driving spring devices and parts which are to be set under the drive of the spring devices in accordance with time, and intermediate means between said spring devices and said parts which comprise devices for driving time set parts, said devices having associated therewith an escapement device for controlling the drive thereof in accordance with time, said devices for driving the time set parts also including supplementary devices for permitting the time set parts to be temporarily restrained against advancing movement and to be subsequently advanced under the power of the spring devices to a supplemental advanced position which is determined by the action of the escapement during the time interval which has elapsed while restraint is imposed.

21. A time controlled apparatus including driving spring devices and parts which are to be set under the drive of the spring devices in accordance with time, and intermediate means between said spring devices and said parts which comprise devices for driving said time set parts, said devices having associated therewith an escapement device for controlling the drive thereof in accordance with time and said intermediate means including provisions for permitting the time set parts to be restrained against advancing movement and also including provisions operative during such restraint for permitting continued operation of the escapement device whereby said escapement may count the duration of time in which restraint is imposed, and means operative after removal of such restraint for causing the spring devices to advance the time set parts to a position determined by the escapement's action during the restraining period.

22. The invention set forth in claim 21 in which the driving means intermediate the spring devices and the time set parts include means for imparting a step by step drive to the time set parts when said parts are permitted to advance free from restraint and which means comes into action to effect supplemental advance of the time set parts when restraint against advance of said parts is removed.

In testimony whereof I hereto affix my signature.

JAMES W. BRYCE.
